UNITED STATES PATENT OFFICE.

HENRY A. WISE WOOD, OF NEW YORK, N. Y., ASSIGNOR, BY MESNE ASSIGNMENTS, TO
WOOD NEWSPAPER MACHINERY CORPORATION, OF NEW YORK, N. Y., A CORPORA-
TION OF VIRGINIA.

BUNDLING DELIVERY FOR FOLDERS.

1,266,738.

Specification of Letters Patent. Patented May 21, 1918.

Application filed October 1, 1912, Serial No. 723,284. Renewed October 11, 1917. Serial No. 196,089.

To all whom it may concern:

Be it known that I, HENRY A. WISE Wood, a citizen of the United States, residing at New York, in the county of New York and State of New York, have invented a new and useful Bundling Delivery for Folders, of which the following is a specification.

This invention relates to an improved delivery mechanism for printing machines especially adapted to that kind of delivery usually used in connection with the folders of web printing presses, but it is capable of general use.

The principal objects of the invention are to provide for automatically and accurately bundling sheets, papers or books, thus doing away with the hand labor now required ordinarily for this purpose; to provide a construction in which this bundling can be done at the high speed necessary in delivering the product from certain modern high speed web presses; and to provide means for delivering the sheets within easy reach of the operator or to a table or elevator. The invention also involves improvements in the features of construction as will appear hereinafter.

Reference is to be had to the accompanying drawings in which—

Figure 1 is a front elevation of a machine constructed in accordance with this invention;

Fig. 2 is a plan of the same; and

Fig. 3 is an enlarged detail view in side elevation of a part of the mechanism.

Heretofore papers have been "fanned" out on running belts and every fiftieth or one-hundredth sheet thrown out of position for counting purposes forwardly by a movable finger at the rear. As the belts carry the sheets from the folder a delivery boy has been employed to reach down and take up in his arms the full number counted.

He then had to jog them into a bundle on a table before he stacked them up and carried them away. At the high rate of speed at which modern web presses of a certain type are run, there is not sufficient time for this work, and it is desirable, of course, to perform it automatically in order to reduce the expense for labor.

This invention is designed for that purpose, and for the purpose of accurately and

automatically counting and bunching the sheets, papers, or books and delivering them at any desired point.

The invention is shown as used in connection with a common form of delivery in which the folded product is delivered in a well known manner from a folding and cutting arrangement 10. It then passes through rollers 11 and fans 12, to traveling endless tapes or belts 13. It is to be understood, however, that the mechanism can be used in connection with any other machine having a continuous delivery. Stationary curved guides 17 are shown for guiding the sheets as they are lowered by the fans. The fans 12 are shown as on a driving shaft 14 which by means of a vertical shaft 15 and 70 gearing drives a cam shaft 16. It is from this shaft that the belts 13 are driven directly. On this shaft is a stop cam 20 which operates an arm of a lever 21. The other end of this lever is adjustably connected 75 with a link 22 pivoted to an arm 23. This arm swings a shaft 24 having arms 25 on each which is a stop 26. These stops oscillate about the shaft 24 and are moved by the cam periodically. Connected with the 80 shaft 24 is a spring 27 for holding the stop back.

A sprocket 30 on the shaft 16 is provided with a chain which operates a shaft 31. This in turn operates an endless carrier 32 85 provided with a plurality of fingers 33 pivotally mounted thereon. These are provided with rigid arms 34 at the ends of which are cam rollers 35. Supported on a shaft 36 are cam plates 37 adjustably 90 mounted by means of slots and bolts 38. These are in position to engage the rollers 35 at certain times and operate the fingers as will be described hereinafter. The carriers are connected to travel faster than the 95 belts 13.

Mounted on the shaft 16 is a hold-back cam 40. Through levers 41, operated thereby, and links 42 this cam accomplishes the oscillation of arms 43 mounted to swing on 100 the shaft 14. Connected with this shaft are a plurality of arms 44 at the ends of which are hold-backs 45. These are adapted to be automatically dropped into position to obstruct the forward movement of the first 105 few sheets of each bundle.

The operation is as follows:—The folded product from the press is delivered in the usual manner from the folding and cutting arrangement through the rollers 11 and fans 12 to the belts 13, preferably one sheet or book at a time. As they are delivered on the belts they strike against the stops 26 and are given a continuous forward motion through most of the period of a complete revolution of the shaft 16. When a predetermined number of sheets have been delivered to the belts the end of the lever 21 suddenly drops from the high part of the cam 20 to the low part. This releases the stops 26 so that they assume their original position. That is, they suddenly go back from the dotted line to the full line position in Fig. 1. Now when the next sheet is delivered on the belts it is obvious that there will be a space between its rear edge and the rear edge of the preceding sheet equal to the distance which the stops fell back. This marks the count. The parts are so timed that at this moment a series of fingers 33 come into position to engage the rear edge of the preceding sheet. Being driven faster than the belts 13, and being controlled by the cam 37, they have a comparatively sudden upward and forward motion. Thus they gradually close up the bundle of sheets until at the dotted line position of these fingers (33^a) the stack of sheets is completed. Then the bundle is carried forward at the same speed by the fingers to be taken off at will by the operator or delivered to a table or elevator. When the fingers reach the position 33^b for delivering, they run off the ends of the cam plates 37 and remain inoperative until again picked up by the opposite ends of these cam plates. At the moment the fingers 33 start to pick up the rear sheet of a bundle the hold-backs 45 are automatically dropped into position by the action of the cam 40. This obstructs the forward movement of the first few papers of the succeeding bundle until enough of their surface comes into contact with the belts 13 to insure their not being carried forward by the faster moving preceding bundle.

In this way it will be seen that the sheets are automatically bunched in bundles of a definite number, as for example, fifty or one-hundred sheets each, and that for practical purposes, the sheets of each bundle are automatically counted out. The mechanism is of such a character that it will operate at the highest rate of speed at which the modern rotary web presses are operated, and its work is accurate and entirely automatic.

Although I have illustrated and described a preferred embodiment of the invention only and shown it as applied to only one type of delivery mechanism, I am aware of the fact that many modifications can be

made in the arrangement of parts and details of construction when applied to this type of delivery, and that it can be applied to other types of delivery either with or without corresponding changes. Therefore, I do not wish to be limited in these respects, but what I do claim is:—

1. The combination with an endless conveyer and means for delivering sheets or the like thereon, of a stop for the rear ends of said sheets, means for continuously advancing said stop in the direction in which the conveyer operates and for then retracting it, and means for moving the sheets forward on the conveyer to form a bundle while the stop is retracted.

2. The combination with a conveyer and means for delivering sheets or the like thereon, of a stop movable adjacent to said conveyer for engaging the rear edges of the sheets, means for moving said stop forward with the conveyer until a predetermined number of sheets have been deposited on the conveyer and for thereafter suddenly retracting said stop, and means to thereafter move the predetermined number of sheets forward relatively to the conveyer to form a bundle.

3. The combination with a conveyer for receiving sheets or the like in successive longitudinal positions on said conveyer, of means for stopping the rear edges of said sheets and advancing a number of them along the conveyer, and additional means for pushing said sheets forward to form a bundle on the conveyer.

4. The combination with a conveyer for receiving sheets or the like in successive longitudinal positions on said conveyer, of means for periodically advancing a number of sheets along the conveyer to form a bundle thereof, and a movable stop for advancing the sheets on the conveyer before said bundling means acts.

5. The combination with a conveyer, and means for delivering sheets or the like thereon, of a stop movable adjacent to said conveyer for engaging the rear edges of the sheets, means for moving said stop forward with the conveyer until a predetermined number of sheets have been deposited on the conveyer and for thereafter suddenly retracting said stop, a movable finger, and means for projecting said finger above the conveyer when the stop is retracted and moving the finger forward to bundle said sheets on the conveyer.

6. The combination with a continuous conveyer, and means for delivering sheets or the like thereon, one at a time, of a stop movable adjacent to said conveyer for engaging the rear edges of the sheets, means for swinging said stop forward with the conveyer until a predetermined number of sheets have been deposited on the conveyer.

and for thereafter suddenly retracting said stop, a movable finger, and means for projecting said finger above the conveyer when the stop is retracted and moving the finger forward faster than the conveyer to bundle said sheets on the conveyer.

7. The combination with an endless conveyer, and means for delivering sheets or the like thereon, of a stop for the rear ends of said sheets, means for continuously advancing said stop in the direction in which the conveyer operates and for then retracting it, and means for moving the sheets forward on the conveyer to form a bundle while the stop is retracted, the last named means comprising an endless carrier under the conveyer, a plurality of sets of fingers pivoted thereon, means for moving said carrier in an endless path, and means for swinging said fingers forward on their pivots while they are on the upper strand of the carrier.

8. The combination with an endless conveyer, and means for delivering sheets or the like thereon, of a stop for the rear ends of said sheets, means for continuously advancing said stop in the direction in which the conveyer operates and for then retracting it, and means for moving the sheets forward on the conveyer in a bundle while the stop is retracted, the last named means comprising an endless carrier under the conveyer, means for operating it, a series of fingers pivoted on said carrier, a cam in position adjacent to the carrier for swinging said fingers forward rapidly above the conveyer as they move up to the upper strand of the carrier, and for releasing them after they have passed beyond a certain point.

9. The combination with an endless conveyer, and means for delivering sheets or the like thereon, of a stop for the rear ends of said sheets, means for continuously advancing said stop in the direction in which the conveyer operates and for then retracting it, and means for moving the sheets forward on the conveyer in a bundle while the stop is retracted, said means comprising an endless carrier below the conveyer, an inclined cam plate adjacent thereto, a series of fingers pivotally connected with the carrier and having an arm provided with a roller for engaging the cam plate.

10. The combination with a conveyer and means for delivering sheets or the like thereon, of means for moving said sheets forward relatively to the conveyer to form a bundle thereon, said means comprising an endless carrier running over a pair of separated guides below the conveyer, means for driving said carrier, a series of fingers pivoted on said carrier, and an adjustably supported fixed cam for swinging said fingers above the conveyer at the rear of the sheets deposited thereon, said cam having a long, substantially straight cam surface held at a

slight acute angle to the upper strand of the carrier and controlling the fingers during their travel along the upper strand only.

11. The combination with a conveyer and means for delivering sheets or the like thereon, of means for moving said sheets forward relatively to the conveyer to form a bundle thereon, said means comprising an endless carrier below the conveyer, means for supporting and driving said carrier, a series of fingers pivoted on said carrier and a fixed cam for swinging said fingers above the conveyer at the rear of the sheets deposited thereon, said cam contacting with and controlling said fingers during the operative part of their travel only.

12. The combination with a conveyer, and means for delivering sheets or the like thereon, of a stop for the rear ends of said sheets, means for continuously advancing said stop in the direction in which the conveyer operates and for then retracting it, and means for moving the sheets forward relatively to the conveyer to form a bundle while the stop is retracted.

13. The combination with a conveyer and means for successively depositing sheets or the like thereon, of a stop for positioning the rear end of each sheet as it is deposited on said conveyer, devices movable relative to said stop for moving a plurality of sheets forward relatively to the conveyer to form a bundle, and means for holding back the sheets deposited on the conveyer after the said devices have commenced the formation of a new bundle.

14. The combination with a conveyer, and means for delivering sheets or the like thereon, of a stop for the rear ends of said sheets, means for continuously advancing said stop in the direction in which the conveyer operates and then retracting it, means for moving the sheets forward on the conveyer in a bundle while the stop is retracted, and means for holding back the sheets deposited on the conveyer after the last named means has acted.

15. The combination with a conveyer and means for delivering sheets or the like thereon, of a stop for the rear ends of said sheets, means for continuously advancing said stop and then retracting it, means for moving the sheets forward on the conveyer in a bundle while the stop is retracted, a cam movable synchronously with the means for operating the stop, a pivoted lever operated by said cam, and means on said lever for engaging the sheets as they are deposited on the conveyer after the bunching means has operated and holding said sheets back against the stop.

16. The combination with a conveyer and means for delivering sheets or the like thereon, of a stop for the rear ends of said sheets, means movable independently of said stop

for moving the sheets forward relatively to the conveyer to form a bundle, and means movable independently of the stop and first named means for holding back the sheets 5 deposited on the conveyer during the formation of the bundle.

17. The combination with an endless conveyer and means for delivering sheets or the like thereon, of an endless carrier located 10 under the conveyer at an angle to it, said carrier approaching the conveyer most closely at a point at a distance from the receiving part of the conveyer, fingers pivoted on the carrier, means for moving said car-

rier in an endless path, and means for swinging said fingers forward on their pivots while they are on the upper strand of the carrier to force them to move sheets on the conveyer forward thereon and form them into complete bundles. 15

In testimony whereof I have hereunto set my hand, in the presence of two subscribing witnesses. 20
